ENVELOPE

Carroll V. Walters, Kansas City, Kans., assignor of
one-half to Henry J. Burasco, Kansas City,
Mo.

Application May 15, 1939, Serial No. 273,734

2 Claims. (Cl. 229—86)

This invention relates to envelopes equipped with tear or rip cords for the opening of such envelopes along three sides. It has long been recognized that if means could be provided to insure the recipient of enveloped mail matter could fully and neatly open the envelope, the inner surface could be used as a display medium for printed advertising matter. The prime object of the present invention therefore, is to produce a practical construction of the character under consideration which can be made on standard envelope machines with very little adjustment. Although tear cords or threads along three sides of envelopes are old, so far as I am aware no means has been provided for the application of such tear cords around three sides of an envelope, except by hand operations. Hand production of such material is impracticable because of cost. The chief object of the present invention, therefore, is to provide an envelope of the general character outlined which is so made that all of the operations can be quickly and easily performed, whereby the envelope can be opened at three sides for exposing matter printed on the interior of the envelope if it bears printed matter. It is also useful as a convenient means of opening envelopes without chance mutilation of their contents.

With the general objects named in view, and others as will hereinafter appear, the invention consists in certain novel and useful features of construction and organization of parts as hereinafter described and claimed; and in order that it may be fully understood, reference is to be had to the accompanying drawing, in which:

Figure 1 is a perspective view of an envelope blank equipped with an affixed tear strip or cord for quick and clean opening of the envelope when formed, along three sides.

Figure 2 is a similar view but with certain of the parts partially folded in the process of forming an envelope.

Figure 3 is a perspective view of the completed envelope ready for use.

Figure 4 is a perspective view of a blank for transformation into an envelope of a slightly modified form, in which the tear cords may be applied simultaneously to two envelope blanks.

Figure 5 is a perspective view of an envelope formed from a blank of the type shown in Figure 4.

Figure 6 is a detail view of one method of applying the tear thread to an envelope blank or filler sheet.

Figure 7 is a detail view of the double tear

thread arrangement used in connection with the simultaneous production of two envelopes of the type shown in Figure 4.

Figures 1 through 3 illustrate the preferred form of envelope, in which 1 is the body or face of an oblong envelope blank, the two long edges of said body being formed with flaps 2 and 3, separated from the body by the fold lines 4 and 5 respectively. The two ends of the body 1 are provided with a pair of similar flaps 6 demarcated from the body by parallel fold lines 7, and set off from the flaps 6 by fold lines 8 extending diagonally as regards the fold lines 7, are similar terminal flaps 9.

15 The flaps 9 have one of their edges alined with the fold lines 5 forming one edge of the body portion 1, and secured along such edge and extending continuously across both flaps 9 and the body 1, is a tear or rip cord 10. The exact means 20 of securing the rip cord in position is immaterial to the invention, but I have found that the most satisfactory method of securing the cord is as shown in Figure 10, where the cord 10 is enrolled in one edge of an adhesive paper strip 11, the paper strip being then applied to the envelope blank with the thread in the position shown.

In the type of construction illustrated in Figures 1 through 3, the edges of the flaps 2, 3 and 6 are provided with adhesive as shown at 12. 30 The envelope is now formed by folding the flaps 9 to overlie the flaps 6 as shown in Figure 2, the adhesive along the edge of the flaps 6 holding said flaps 9 in position to avoid bulking in the mouth of the envelope as will hereinafter appear, although it is to be understood that the adhesive on the flaps 6 is not essential. This operation brings the tear cord 10, carried by the edges of the flaps 9 into parallelism with the fold lines 7 demarcating the ends of the blank 1, ultimately forming the ends of the envelope. The two flaps 6 and 9 are now folded over on lines 7 to overlie the body 1, and the flap 3 is folded to overlie said ends, see Figure 3, and the adhesive on the edges of the flap 3 secures the parts in final

40 envelope forming position. For convenience, one corner of the envelope may be weakened as at 13, and the face of the envelope may carry any suitable signal (not shown) calling attention to the weakened corner. When the corner at 13 is torn off by the recipient of the envelope, one end of the cord 10 is retained within the torn-off corner and by pulling on the cord the three sides of the envelope are torn or opened, as will be readily understood.

45 50 55 Manufacturing cost may be saved by applying

the tear strip to two envelopes in a single operation as shown in Figures 4 and 5. In this construction, 14 and 15 are respectively the front and rear body portions of an envelope arranged in opposing pairs along the center line of the paper stock to be severed along such center line as will hereinafter appear. Since the construction of this type of envelope is shown in duplicate, only one envelope will be particularly described. The back body portion 15 is formed at each end with a flap 16 demarcated by a fold line 17, and said flaps 16 carry second flaps 18 demarcated by fold lines 19 angularly arranged with respect to the fold lines 17. Extending along the center line of the double blank is a pair of tear cords 20 which are preferably of the construction shown in Figure 11, in which a pair of threads or cords 20 are secured on opposite sides of the center line of the blank by an adhesive equipped paper strip 21. By severing the blank on its center line between the cords, a pair of duplicate envelope blanks are formed.

The envelope is completed by folding the flaps 16 and 18 down overlying the back body portion 15, and then the back body portion is folded to overlie the front body portion 14, the flaps 16 and 18 thus being between the front and back faces of the envelope. The ends of the front body portion 14 are formed with gummed flaps 30

22, which are now folded down on the outer side of the back body portion 15 and are glued or gummed in position, thus completing the envelope as it appears in Figure 5.

5 I claim:

1. An enveloping blank comprising a body portion, a flap at one end of the body portion and separated therefrom by a fold line, a second flap projecting from the first flap and separated therefrom by a fold line in angular relation to the first fold line, said second flap having a free edge aligned with one side edge of the body portion and being adapted to be brought into parallelism with the first fold line, and a flexible severing element extending along the aligned edges of the body portion and said second flap.

2. An enveloping blank comprising a body portion, flaps at opposite ends of the body portion and separated therefrom by parallel fold lines, a pair of similar second flaps projecting from the first flaps and separated therefrom by fold lines extending in opposite angular relation to the first fold lines, said second flaps each having a free edge aligned with one side edge of the body portion and being adapted to be brought into parallelism with the first fold lines, and a flexible severing element extending along the aligned edges of the body portion and said second flaps.

CARROLL V. WALTERS.
